UNITED STATES PATENT OFFICE.

EMORY GLENN SIMPSON, OF DETROIT, MICHIGAN, ASSIGNOR TO FISHER BODY CORPORATION, OF DETROIT, MICHIGAN, A CORPORATION OF NEW YORK.

HANDLE ASSEMBLY.

Application filed December 23, 1920. Serial No. 432,800.

To all whom it may concern:

Be it known that I, EMORY GLENN SIMPSON, a citizen of the United States, residing at Detroit, in the county of Wayne and State of Michigan, have invented certain new and useful Improvements in Handle Assemblies, of which the following is a specification.

This invention relates to handle assemblies, especially to door handles for automobiles. It has for its object a door handle spindle and escutcheon plate assembly which permits of a certain irregularity in the placement of the lock without interfering with the operation of the handle.

In present general practice it is customary to provide a shoulder between the handle and the spindle. An escutcheon plate is fitted against this shoulder and locked in place by a split washer dropped into a groove in the spindle. This locks the handle and spindle to the escutcheon plate. A certain amount of looseness is had so that the escutcheon plate can wobble slightly on the spindle, but it has been often found necessary when the lock case was assembled on the door to bend the spindle in order to get the escutcheon plate to properly set upon the outside of the door panel. The obvious reason for this is that the lock casing can never be set two times in exactly similar positions. Hence the position of the square opening through the roll back varies and in order to get the escutcheon plate and the square spindle in the proper position, in a great many cases, it has been necessary to bend the spindle to compensate for this variety of locations.

It is the object of the present invention to do away with this trouble and provide an escutcheon plate that is neatly assembled upon the handle and spindle.

In the drawings,—

Fig. 1 is an elevation of the handle and spindle showing the escutcheon plate in section and before the same has been locked onto the handle stem.

Fig. 2 is a similar view showing the same parts after the escutcheon plate has been locked onto the handle stem.

Fig. 3 is a section on the line 3—3 of Fig. 2.

Fig. 4 is a section on the line 4—4 of Fig. 2.

Fig. 5 is a section on the line 5—5 of Fig. 2.

a designates a common form of door handle; *b* the handle stem, and *c* the square spindle, whose extreme end is adapted to go through the square hole of the roll back ⁶⁰ of the door lock (not shown). The cast or stamped escutcheon plate *d* is cast or stamped in the form shown in Fig. 1, namely, the usual plate portion with oppositely-directed bosses, the rear one *e* being cast with a segmental inner surface adapted to fit over the spherical head or escutcheon plate seat *f* between the stem *b* and the spindle *c*. The front boss *g* has a cylindrical inner surface so that it can be fitted over the spherical head *f*. It is then spun down, as shown in Fig. 2, by a spinning tool. This locks the escutcheon plate on the spherical head *f* but still permits it to tilt, twist and turn thereon within quite wide limits as ⁷⁰ the joint is a universal or ball and socket joint.

Obviously the lock with its roll back can be considerably displaced from a true position of parallelism with the escutcheon plate and the roll back square hole out of alignment with the axis of the opening through the escutcheon plate, yet the spindle and handle will properly function and revolve in the escutcheon plate because ⁸⁰ this spherical head has a universal mounting in the bosses of the escutcheon plate.

What I claim is:

1. A handle assembly, having in combination, a handle, a handle stem, a spindle, a ⁹⁰ spherical head between the spindle and the handle stem, and an escutcheon plate locked by its own shape on the spherical head to have universal movement thereon.

2. A handle assembly, having in combination, a handle, a handle stem, a ball-like head adjoining the handle stem, a spindle extending from the ball-like head, and an escutcheon plate provided with laterally-extending bosses to engage over the ball to confine it at both sides of the plate and forming a ball and socket joint on said ball-like head.

3. A handle assembly, having in combination, a handle, a stem, a spindle, a spherical head between the latter two, and an escutcheon plate comprising a member formed with a rear boss adapted to engage ¹⁰⁵

- the spherical head at the rear and by the forward boss turned down on the forward portion of the spherical head to lock the same thereon in a ball and socket joint.
4. A handle assembly, having in combination, a handle, a stem, a spindle, and a spherical head between the spindle and the stem, and an escutcheon plate provided with a rearwardly-extending boss and a 10 forwardly-extending boss around the central opening, the rearward boss fitting over the rear portion of the spherical head and the forward boss being spun down over the forward portion of the spherical head 15 after the same has been assembled there-over.
5. A handle assembly, having in combination, a handle, a stem, a spindle, and an escutcheon plate seat between the spindle 20 and the stem, and an escutcheon plate
- provided with a plate member for attachment to the door panel and a central portion having a rearwardly-extending part adapted to engage the rear of the escutcheon plate seat and the forwardly-extending portion adapted to engage the forward part of the escutcheon seat and be turned thereto over to lock the escutcheon plate thereto.
6. A handle assembly, having in combination, a handle, a stem, a spindle, an 25 escutcheon plate seat between the spindle and the stem, and a cast escutcheon plate provided with a rearwardly-extending boss adapted to engage the escutcheon plate seat and with a forwardly-extending boss 30 adapted to be engaged over the escutcheon plate seat and turned down over the same to lock the escutcheon plate to said seat.

In testimony whereof I affix my signature.
EMORY GLENN SIMPSON.
